UNITED STATES PATENT OFFICE.

FRANK G. FREESE, OF ALDAN, PENNSYLVANIA.

INTERNAL-COMBUSTION MOTOR AND VALVE THEREFOR.

1,299,320.

Specification of Letters Patent. Patented Apr. 1, 1919.

Application filed March 2, 1918. Serial No. 219,999.

To all whom it may concern:

Be it known that I, FRANK G. FREESE, a citizen of the United States, residing at 111 Woodlawn ave, Aldan, in the county of 5 Delaware and State of Pennsylvania, have invented new and useful Improvements in Internal-Combustion Motors and Valves Therefor, of which the following is a specification.

10 The invention relates to internal combustion motors, and has for an object to provide a novel form of internal combustion motor and valve therefor, to result in simplicity of operation, ready removal of any of the 15 valve parts for the purpose of cleaning or grinding; proper registration of the various ports, associating the motor body with the valve as to the admission and exhaustion of gases, and therefore the effective operation 20 of a motor of the character that will be described.

Among other features, the invention comprehends a valve structure which is of a unitary construction, in that the valve proper 25 can be removed in its entirety for the purpose of grinding or cleaning, and in its entirety can be adjusted in its casing or sleeve, so as to bring about proper registration of the various port openings.

30 Further the invention comprehends a motor and valve which can be so arranged with respect to the usual timing mechanism, that there will be no chance of disarrangement of the timing mechanism relative to 35 the motor proper and the valve, as to the explosion of the gases in the cylinders.

In the further disclosure of the invention, reference is to be had to the accompanying drawings, constituting a part of this specification, and in which similar characters of reference denote corresponding parts in all the views, and in which—

40 Figure 1 is a vertical longitudinal sectional view taken through a form of my motor, part, however, being shown in side elevation.

Fig. 2 is a fragmentary plan view taken through the valve structure.

Fig. 3 is a plan view of the sleeve.

45 Fig. 4 is a sectional view taken through the sleeve on the line 4—4 of Fig. 3.

Fig. 5 is an elevation of the valve body.

Fig. 6 is a sectional view taken on the line 6—6 of Fig. 5, and

50 Fig. 7 is a diagrammatic view showing the cylinders of the motor and the respec-

tive positions of the parts of the valve to disclose the cycle of operation of the motor.

Referring more particularly to the views, the numeral 10 indicates the motor in its entirety, and which comprises the usual block 11 formed to provide cylinders 12—12^a—12^b and 12^c, with corresponding pistons 13—13^a—13^b and 13^c respectively. The block 11 may be suitably water-jacketed by 60 providing a water-jacket 14, and the pistons 13—13^a—13^b and 13^c respectively are connected to connecting rods 15—15^a—15^b and 15^c, the latter having suitable connection with a crank shaft 16, journaled in the usual 65 crank case 17 of the motor.

The upper part of the block 11 is formed to provide a casing 18, in which are formed ports 19—19^a—19^b and 19^c which may be more particularly termed cylinder ports, to 70 differentiate from other ports hereinafter more fully described. The casing 18 has a chamber 20 suitably tapered and in which is arranged a sleeve 21, the sleeve being tapered and secured rigidly in the casing by 75 a driving fit. An oil cup of any desired form, indicated by the numeral 22, may be secured in the casing 18 to supply oil, which operating along a channel 23 in the sleeve, will pass through openings 24 therein to 80 supply lubrication to the valve, that will be hereinafter set forth. The sleeve is provided with spaced openings 25—25^a—25^b and 25^c, communicating with an inlet chamber 26 of the casing through which the 85 vapor or gas that is to be exploded, passes into the motor, and the sleeve is also provided with openings 27—27^a—27^b and 27^c through which the exhaust gases will pass to an exhaust chamber 28, it being understood 90 that the openings 25—25^a—25^b and 25^c may be better termed, inlet openings of the sleeve, and the openings 27—27^a—27^b and 27^c, outlet openings. The sleeve 21 is further provided with openings 29—29^a—29^b and 29^c 95 which communicate directly with respective cylinder ports 19—19^a—19^b and 19^c, shown in Fig. 1.

Threaded in one end of the casing 18 is a plug 30 which carries a screw 31, and disposed within the sleeve 21 is a valve 32 of a tapered formation to fit the sleeve, with one end of the valve abutting against the inner end of the adjusting screw 31, the other end of the valve carrying a shaft 33 100 extending exteriorly of the casing, on which is secured a suitable toothed wheel 34, which

may be in the nature of a sprocket wheel or otherwise, constituting a driving member that may have suitable connection by a chain 35 or by gears, to a sprocket wheel 36 keyed on the crank shaft 14, so that a desired ratio of the speed of the driving element 34 can be obtained through the particular size of the driving element 36 on the driving crank shaft 14.

- 10 The valve 32, as mentioned heretofore, is tapered to fit perfectly within the sleeve, and a series of compression washers or other elements 37 are placed against the enlarged end of the valve, with a suitable plug 38 threaded in the casing 18, and forming a bearing for the valve shaft 33, as clearly shown in Figs. 1 and 2.

The valve 32 is formed with a series of gouged-out recesses or ports, which I may term valve ports, and which I indicate by the numerals 39^a—39^a—39^b and 39^c, the valve ports being arranged in what might be termed a staggered position upon the valve as to its periphery, so that in the rotation 25 of the valve within the sleeve, these ports will be brought into or out of registration or communication with the sleeve openings 25—25^a—25^b and 25^c, 27—27^a—27^b and 27^c, 29—29^a—29^b and 29^c, and therefore into and 30 out of registration with the respective cylinder ports 19—19^a—19^b and 19^c.

From what has been described of the valve and the encircling valve sleeve, it will be clear that a desirable relation between the 35 valve ports and the sleeve openings or ports can be easily obtained in the assembling of the two structures, by associating the valve and sleeve prior to their connection or relation with the motor itself, and whereby the 40 ports of the valve can be easily marked thereon through the openings of the sleeve, and the ports then gouged out or produced in the desired manner.

Referring now to Fig. 7, it will be seen 45 that with the valve and sleeve arranged with respect to the cylinder ports and motor body, the desired operation will take place as shown in Fig. 7, where, for instance, when the piston 13 is assuming a downward stroke 50 to suck in to the cylinder 12 a quantity of vapor or gas, the particular port 39 of the valve will be in position to provide the desired passage from the inlet 26 into the port 39, and through the port 25 of the sleeve 55 to the cylinder port 19, so that a complete open passage will be formed, whereby the gas can be readily taken in, and will be sucked in with the downward movement of the piston 13. At this time, the second piston 60 ton 13^a will be on an upward stroke to compress gas that has been already received in its particular cylinder 12^a, and at this time the valve being in position to permit of gas being sucked into the first cylinder 12, will 65 be closed as to the second cylinder, by reason

of the valve port 39 being out of registration with the sleeve port 29^a, and so also with respect to the cylinder 12^b, its piston 13^b being on the exhaust movement, whereby it will be moving upwardly to scavenge the 70 particular cylinder 12^b, the valve port 39^b will be in position to provide a passage from the cylinder 12^b, by reason of the cylinder port 19^b being in direct registration with the port 29^b of the sleeve, the port 39^b of the 75 valve and the exhaust port 28. And so also the fourth cylinder 12^c, having its piston in uppermost position to come down at the point of compression and compress the gas in the cylinder, the cylinder port 19^c will 80 be closed by reason of the position of the valve 32, as shown in Fig. 7.

From the foregoing it will thus be seen that regardless of the particular arrangement of the cylinders, their ports and the 85 sleeve ports with respect to the valve and its ports, the cycle of operation will be such that the various parts will coöperate to bring about the taking-in of gas in one cylinder, while another is under compression, a third 90 on exhaust and a fourth on compression, and with this arrangement in mind, it will be seen that by having the valve shaft in direct association with a suitable timing mechanism 40, the explosion of the mixture 95 in a particular cylinder of the motor, will be accomplished at the time when its piston has reached the proper position in said cylinder, and the valve port to that cylinder is closed.

With the construction set forth it will be seen that one of the aims is to provide a clear passage from the in-take manifold to the various registering ports of the sleeve, the valve and the cylinder, when a particular cylinder and its piston are prepared to receive the mixture, and so also on the compression, exhaust and combustion, it will be seen that in exhausting the burnt gas, the same will pass out through the exhaust port 105 28, a free passage being provided therefor.

By having the valve 32 provided with an integral valve shaft 33, a direct rotating connection can be secured through the medium of the connection with the crank shaft, 115 whether it be by gear or chain, or otherwise, and that in this arrangement a positive connection is also secured with the timing mechanism so as to greatly simplify this part of the operation and procedure, and it will be 120 clear that with very little trouble, the valve can be removed and the cylinder also, if desired, for the purpose of removing carbon deposits, or for grinding down the valve, or truing up the openings in the sleeve.

It will of course be understood that I do not limit myself to the particular disclosure set forth herein; that various slight changes may be made from the construction set forth in the drawings and described in the speci- 125

ification, without departing from the spirit of the invention, and that the scope of the invention is defined in the appended claim.

I claim:

5 In an internal combustion engine, including a plurality of cylinders, a valve casing associated with the cylinders and provided with ports communicating with the interior of said cylinders, said valve casing being formed to provide a central tapered sleeve portion and enlarged portions at the sides thereof constituting inlet and exhaust chambers, said sleeve portions being provided 10 with ports communicating respectively with 15 said inlet and exhaust chambers; a tapered

rotary valve disposed within said sleeve portion and provided with ports adapted to register with said first and second named ports, a plug disposed within the smaller end of said sleeve portion, a screw threaded through said plug and engaging the smaller end of said valve, a plug threaded into the larger end of said sleeve portion, and a plurality of compression rings disposed between said last named plug and the larger end of said valve whereby to hold said valve in close fitting relation within said sleeve portion.

In testimony whereof I affix my signature.

FRANK G. FREESE.
